Attorney

UNITED STATES PATENT OFFICE.

CHARLES M. STAFFORD, OF HERRICK, ILLINOIS.

GRAIN-CAR DOOR.

1,332,311.

Specification of Letters Patent.

Patented Mar. 2, 1920.

Application filed January 4, 1919. Serial No. 269,603.

To all whom it may concern:

Be it known that I, CHARLES M. STAFFORD, a citizen of the United States, residing at Herrick, in the county of Shelby and State of Illinois, have invented certain new and useful Improvements in Grain-Car Doors, of which the following is a specification, reference being had to the accompanying drawings.

10 This invention relates to certain improvements in grain car doors, and it is an object of the invention to provide a device of this general character with novel and improved means for preventing the waste of grain by leakage while a car is in transit.

It is also an object of the invention to provide a novel and improved door provided with yieldable means for contact with the floor of the car when the door is in closed 20 position so that leakage beneath the door is eliminated.

The invention consists in the details of construction and in the combination and arrangement of the several parts of my improved grain car door whereby certain important advantages are attained and the device rendered simpler, less expensive and otherwise more convenient and advantageous for use, as will be hereinafter more 30 fully set forth.

In order that my invention may be the better understood, I will now proceed to describe the same with reference to the accompanying drawings, wherein:

35 Figure 1 is a view in elevation of the inner face of my improved car door in applied position with a part omitted, the co-acting portion of the car being illustrated partly in elevation and partly in section;

40 Fig. 2 is a view in top plan of the structure as disclosed in Fig. 1;

Fig. 3 is an enlarged fragmentary vertical sectional view taken through the lower marginal portion of the door midway its 45 length and through the floor of the car body; and

Fig. 4 is an enlarged sectional view taken substantially on the line 4—4 of Fig. 1, certain of the parts being in plan.

50 As disclosed in the accompanying drawings, W denotes the side wall of a car body, and which is provided with a door opening O having its ends defined by the vertically disposed jambs or facings J.

55 D denotes a grain door adapted to be disposed across the lower portion of the open-

ing A and which is of a length greater than the width of the opening O so that the end portions of the door D will overlie the inner faces of the jambs or door facings J. 60 Each end portion of the door D is provided with a longitudinally disposed slot 1 through which is adapted to be directed a shank 2. The shank 2 has its outer end portion provided with a laterally directed 65 extension 3 overlying an outer face of the jamb or door facing J. The extension 3 is also provided with inwardly directed teeth 4 or the like adapted to impinge or penetrate the adjacent surface of the jamb or door facing J. 5 denotes a plate contacting with the inner face of the door D and disposed over the slot 1. Coacting with the outer face of the plate 5 is a clamping nut 6 threaded upon the inner extremity of the 70 shank 2. The nut 6 is provided with an operating lever or handle 7 whereby the same may be readily rotated either to secure the door in closed position or to effect the release of the door. It is believed to be 75 obvious that upon rotation of each of the nuts 6 in one direction the door D will be effectually held in applied or closed position without the necessity of nails or kindred securing members.

80 Disposed longitudinally of the lower marginal portion of the door D and overlying the inner face of said door, is an elongated resilient strip 8 of a length substantially equal to the width of the door opening O 90 and the underface of said strip has applied thereto a lamination 9 of felt or other compressible fabric or material, and which is adapted to directly contact with the floor F of the car body. Each end portion of the strip 8 is provided with a longitudinally disposed slot 10 through which is directed a headed shank 11 or the like. The shanks 11 serve to hold the strip 8 to the door D while the slots 10 permit the strip 8 to have 95 the requisite flexure in order to assure the proper contact of the strip 8 or more particularly the lamination 9 with the floor of the car to prevent waste of grain or the like by leakage and particularly when the 100 car sags, turns or twists.

105 The lower marginal portion of the door D substantially midway its length has secured to its inner face a pair of spaced vertically disposed strips or cleats 21, and under which the strip 8 is disposed, and arranged between said strips or cleats 21 is

an expansible member 12 herein disclosed as a conventional type of coil spring. The lower end of the member 12 contacts with the central portion of the strip 8, while the 5 upper end thereof is adapted to engage the under surface of a horizontally disposed lever L. One end portion of the lever is pivotally engaged as at 14 with the inner face of the door D adjacent an end thereof 10 and is mounted for movement in a vertical path. Substantially midway its length the lever L has depending therefrom a pair of longitudinally spaced blocks 15 between which the upper end portion of the member 15 12 is arranged whereby proper coaction between the member 12 and the lever L is assured.

The opposite or free end portion of the lever L is adapted to engage the upper end 20 portion of a strip or cleat 16 and is held in such contact by a hook member 17 carried by the strip or cleat 16 and coacting with an eye 18 carried by the adjacent end portion of the lever L. When the lever L is 25 in contact with the strip or cleat 16 the member 12 is placed under such tension or compression to assure the strip 8 being constantly urged toward the floor 9 so that the resultant contact of the lamination 9 with 30 the floor F will effectually prevent waste of grain or the like by leakage below the door D.

When it is desired to remove the door it is only necessary that the hook member 17 35 be disengaged from the eye 18 and to remove the nut 6 hereinbefore referred to.

In order to prevent bulging or the like of the door D by the weight of the grain within the car body, I find it of advantage 40 to provide the central portion of the door D with an inwardly directed eye member 19 to which a chain 20 or the like is engaged, and which chain 20 is suitably anchored to a similar grain door at the opposite side of 45 the car body or to any other suitable part of the car body.

I also find it of advantage to secure to the outer faces of the strips or cleats 21 a flat member or board 22 which extends the entire length of said strips or cleats 21 and terminates above the lever L. The upper end portion of the member or board 22 is provided with an inwardly directed extension or flange 23 contacting with the inner 55 face of the door D. By use of the member or board 22 and the extension or flange 23 it will be at once self evident that the member 12 is protected from the grain or the like within the car so that the functioning of the 60 member 12 is unhindered.

From the foregoing description, it is thought to be obvious that a grain car door

constructed in accordance with my invention is particularly well adapted for use by reason of the convenience and facility with 65 which it may be assembled and operated, and it will also be obvious that my invention is susceptible of some change and modification without departing from the principles and spirit thereof, and for this reason 70 I do not wish to be understood as limiting myself to the precise arrangement and formation of the several parts herein shown in carrying out my invention in practice except as hereinafter claimed. 75

I claim:

1. In combination with a door, a resilient strip carried by a marginal portion of the door, a lever pivoted to the door, an expansible member interposed between the strip and lever, the movement of the lever in one direction placing the expansible member under pressure, means for holding the lever in such position, and spaced members carried by the lever between which an end portion of the expansible member is seated. 80

2. In combination with a door, a resilient strip disposed along the lower marginal portion thereof and carried by the door, a lever positioned above the strip and pivoted at one end portion to the door, a member carried by the door with which the free end portion of the lever engages to limit the movement of the lever toward the strip, releasable means for holding the lever to said member, an expansible member interposed between the central portions of the strip and the lever, said expansible member being placed under tension by the lever when said lever is held by the member, spaced members depending from the lever between which the upper end portion of the expansible member is seated. 90

3. In combination with a door, a resilient strip disposed along the lower marginal portion thereof, the opposite end portions of said strip having slidable connection with the door, a lever positioned above the strip and pivoted at one end thereof to the door, a member carried by the door with which the lever engages to limit the movement of the lever toward the strip, releasable means for holding the lever to said member, an expansible member interposed between the center portions of the strip and the lever, 100 said expansible member being placed under tension by the lever when said lever is held by the first named member. 105

In testimony whereof I hereunto affix my signature in the presence of two witnesses. 110
CHARLES M. STAFFORD.
